Des. 235,422
Patented June 17, 1975

235,422

HOUSING FOR BOTTOM CURRENT METER

Shale J. Niskin, 2941 Lucaya St.,
Miami, Fla. 33133

Filed Apr. 1, 1974, Ser. No. 456,728

Term of patent 14 years

Int. Cl. D10—04

U.S. CL. D10—96

FIG. 5

FIG. 6

FIG. 1 is a side elevational view of a housing for a bottom current meter showing my new design.

FIG. 2 is a similar view showing the obverse side.

FIG. 3 is a similar view with the housing having rotated about its axis in an arc of 180° from that shown by FIG. 1.

FIG. 4 is a similar view showing the obverse side of that shown by FIG. 3.

FIGS. 5 and 6 are front and rear end views respectively.

I claim:

The ornamental design for a housing for bottom current meter, substantially as shown.
